United States Patent

Des. 236,627
Patented Sept. 2, 1975

236,627

TELEPHONE HANDSET

John Forrest Henshew, Mill Valley, Victor Herbert Henshaw, Alamo, and Charles Phillips, San Francisco, Calif., assignors to Litton Business Telephone Systems, Inc., Sunnyvale, Calif.

Filed Dec. 18, 1974, Ser. No. 533,857

Term of patent 14 years

Int. Cl. D14—03

U.S. Cl. D26—14 A

Fig. 1

Fig. 2

Fig. 3

Fig. 4

Fig. 5

Fig. 6

Fig. 7

FIG. 1 is a top perspective view of a telephone handset showing our new design;

FIG. 2 is a bottom perspective view thereof;

FIG. 3 is a bottom plan view thereof;

FIG. 4 is a right-hand side elevation thereof, the left-hand side elevation being essentially a mirror image of FIG. 4;

FIG. 5 is a top plan view thereof;

FIG. 6 is a left end view thereof; and

FIG. 7 is a right end view thereof.

We claim:

The ornamental design for a telephone handset, as shown and described.
